UNITED STATES PATENT OFFICE.

HENRY LEONARD HEATHCOTE, OF COVENTRY, ENGLAND, ASSIGNOR TO RUDGE-WHITWORTH, LIMITED, OF COVENTRY, ENGLAND.

METHOD OF AND MEANS FOR GAUGING METAL OR OTHER ARTICLES.

Application filed February 10, 1920. Serial No. 357,731.

To all whom it may concern:

Be it known that I, HENRY LEONARD HEATHCOTE, a subject of the King of Great Britain, residing at Rudge Works, Crown

5 Lane, Coventry, in the county of Warwick, England, have invented certain new and useful Improvements in the Method of and Means for Gauging Metal or Other Articles, of which the following is a specification.

10 This invention relates to determining or selecting operations known as gauging and grading as carried out upon nominally similar articles such, as, say for example, bearing balls.

15 It is known that, provided the engaging surfaces have a high finish, a metal sphere or cylinder will pass through a ring having an internal diameter slightly less than the diameter of the sphere or cylinder, and that 20 little or no damage will result to either piece so long as the elastic limits of the metal are not exceeded. In passing a plug through a ring, said plug being nominally 1.125" in diameter, our experiments have shown 25 that a variation of one ten-thousandth of an inch may result in a difference of about fifteen pounds in the effort required; that the difference may be increased or decreased 30 by varying the engaging pieces, and that a similar but less pronounced result is obtained with snap gauges and flat or curved articles.

The object of the present invention is to 35 make use of the foregoing facts to facilitate the exact determination required in such operations.

The invention consists in a method of 40 performing upon articles at least one of the operations known as gauging and grading according to which differences between nominally similar specimens are determined by comparison of the forces required to 45 effect relative movement, while in contact, of the articles, and size determining means, such for example as a gauge, micrometer or other device.

The invention further consists in a method 50 according to the preceding paragraph or means for carrying the same into operation, in which the gauged articles are automatically collected in various groupings corresponding to the forces which have been necessary to effect movement in relation to the size determining means.

55 The invention further consists in a method

or means as indicated in which the deflection under different forces of resilient means supporting the size determining means determines the difference and in addition or alternatively effects the automatic grouping of the articles.

The invention further consists in providing a method of and a means for gauging and in addition or alternatively grading metal or other articles, in which the resistance offered between the gauge and the article when moved in relation to one another may be indicated on the dial of a spring balance or the like, from which an accurate reading or deduction may be made.

The invention further consists in a method of and a means for gauging and in addition or alternatively grading suitable metal or other articles in which a definite or succession of definite pressures is applied to overcome the resistance offered to the article in passing through or between the gauging surface or surfaces of an appropriate gauge, with or without means for conducting the operation mechanically and collecting the articles of different sizes in different receptacles.

The invention further consists in a method of, and a means for gauging and grading articles as indicated in the preceding clauses, in combination with a spring balance or like means for indicating pressures or reading dimensions.

Referring now to the accompanying more or less diagrammatic drawings:

Figure 1 shows a micrometer gauge supported on a spring balance for operating in accordance with the invention.

Figures 2 and 3 show a modified micrometer instrument for operating upon articles of a greater range of sizes.

Figures 4 and 5 show an apparatus for operating upon bearing balls or other articles.

Figure 6 shows another form of apparatus for operating upon similar articles such as bearing balls.

Figure 7 shows a somewhat modified apparatus of the type shown in Figure 6.

In the construction shown in Figure 1, 105 *a* is a micrometer attached by any suitable means to the table *b* of a spring balance *c*. In using such an apparatus the anvils *d* *d'* of the micrometer are set at a distance apart slightly less than the smallest of the articles 110

which are to be gauged and the forces required to pass the articles between the anvils of the micrometer are noted upon the dial of the spring balance, the sizes being determined by reference to the deductions formed from gauging in like manner articles of known differences of size.

In the construction shown in Figures 2 and 3, rectangular blocks $e' e'$ are fastened 10 between longitudinal tying members $f' f'$ by screws g accommodated in slots in the longitudinal members, a third block h being provided adjacent to the block e' having an actuating screw h' for facilitating adjustment of the block e' . The two blocks $e' e'$ are provided with anvils or hardened gauging faces $i' i'$.

In using this apparatus an appropriate standard is placed between the gauging surfaces $i' i'$, and the blocks clamped with the faces in contact with the standard, a suitable pressure between the faces and the standard being adjusted. The force necessary to move the standard between the faces may 20 then be ascertained by placing the apparatus upon a spring balance as indicated in Figure 1. Another standard of slightly larger dimensions may then be gauged in the same manner and the reading of the balance 25 again noted after which any articles of dimensions sufficiently approximating to those of the standards may be inserted and their sizes determined by reference to the balance reading indicating the force necessary to insert them between the gauging surfaces.

Figures 4 and 5 show a piece of apparatus 30 suitable for gauging and grading bearing balls which have already been gauged to about one ten-thousandth of an inch. In this machine a shaft j driven by a wheel j' 40 operates by the crank pin j^2 a lever k which at its other end is connected by links k' to a disc or carrier l having around its edge a ring of slidably mounted pressing members l' provided with collars l^2 adapted to support any desired number of disc weights l^3 . The disc l is free to slide up and down upon a central guide m , upon the lower portion 50 of which there is rotatably mounted a table n carrying a series of gauges n' corresponding to the series of pressing members l' . The gauges n' may preferably be split and mounted in holders n^2 provided with means for compressing or closing the rings to any 55 desired extent.

Beneath the table n is arranged a series 60 of orifices o corresponding to the number of pressing members l' and each provided with a tube or other conduit o' leading to a suitable receptacle for receiving the articles after they have passed the gauges.

The table n is adapted to be moved intermittently around the guide m by any suitable motion, say for example, the interrupted 65 worm p gearing with teeth on the boss

of the table n and operated by the shaft p' , bevels p^2 and vertical shaft p^3 from the main shaft j .

The disc l is reciprocated upon the guide m and between each movement the disc n is moved a distance equal to the space between the pressing members l' . The gauges n' are fed with balls to be gauged, and as the pressing members l' are lowered thereon any ball of an appropriate size will be forced through 70 its gauge and carried by the conduit into the corresponding receptacle. A ball which fails to pass under the pressure of the first member which acts upon it will be moved on to the next and so on until it has been forced through the gauge into a receptacle 75 corresponding to the increase of pressure or number of applications of a similar pressure required. The pressure on each plunger may, if desired, be varied by being weighted, or if preferred a lever system or other form of loading may be employed. The pressures exerted by the members l and the sizes of the gauging rings are so adjusted that successively delivered lots differ in size only to 80 the desired extent, and as each application of force to a ball is in the nature of a tap or slight blow, either the number of taps of equal force or the number of taps of gradually increasing force may be employed for 85 the purpose of selection.

In the construction shown in Figure 6 a gauge n' is carried upon a holder n^3 sliding in a guide n^4 and supported upon a coiled spring n^5 . A pressing member l^4 working 90 in a guide l^5 and operated by a lever l^6 is lowered upon the ball q supported in the gauge n' until the pressure exerted by the spring n^5 is sufficient to force the ball 95 through the gauge. The holder n^3 is provided with a toothed rack n^6 gearing with the teeth of a quadrant r carried upon one arm r' of a cranked lever, the other arm r^2 of which gears by a toothed quadrant r^3 100 with a bevel wheel s' connected to a pan s rotatably mounted upon a stud s^2 .

The pan s is divided into a series of compartments and as it is turned by the downward movement of the holder n^3 a compartment corresponding with the position reached by the holder and consequently with the pressure exerted by the spring n^5 will be brought underneath the ball q at the moment it is pressed through the gauge n' . In order to prevent a sudden return of the 110 holder n^3 and the delivery of a ball to a wrong compartment a pawl t is fitted to engage ratchet teeth n^7 upon the holder n^3 , thus preventing its return until the pawl t 115 has been released.

Figure 7 indicates a modified form of the type of mechanism last described; a gauge holder u is provided with a curved passage u' leading out upon the side of the holder u and registering with a series of ports v, v' , 120

v^2 and v^3 formed in the side of the guide n^4 .

In this construction the holder is supported upon a spring n^5 and provided with a pawl t as in the form last described, but in this case the ports v to v^3 are each provided with tubes leading to separate receptacles taking the place of the rotatable and divided pan s , and the balls pass into one or the other of the ports in accordance with the pressure which has been necessary to enable them to pass through the gauge. To ensure the holder u registering correctly with one or other of the ports v to v^3 , a pawl or catch w may be provided to engage teeth x formed in the pressing member l^4 .

It will be seen that with the apparatus as hereinbefore described, very accurate gauging may be obtained; for example, bearing balls of .625 inch in diameter which have already been gauged so that the variation in diameter does not exceed one ten-thousandth of an inch may, by operating in accordance with the invention, be further separated into 2, 3, 4 or more different sizes as desired. The constructions hereinbefore described are given by way of example only, and it will be easily seen that the various methods of loading and other modifications may be introduced without in any way departing from the spirit of this invention.

Having now described my invention, what I claim as new and desire to secure by Letters Patent is:—

1. The method of gauging articles which consists in applying said articles to a gauging opening and indicating the differences between said articles by the differences in resistance afforded by a wall of said opening to the articles.

2. The method of ascertaining small differences in the characteristics of similar articles consisting in moving said articles relative to a gage, said gage and articles being so related in size and form to one another that the relatively moving articles and gage when applied the one to the other deform one another elastically, and utilizing the magnitude of the force required to produce such relative motion for determining the desired characteristics of said articles.

3. A method of grading articles according to small differences in the characteristics of said articles, consisting in moving said articles relative to a gage, said gage and articles being so related in size and form to one another that the relatively moving articles and the gage touch, and to a slight extent deform one another elastically, and utilizing the magnitude of the force required to produce such relative motion for determining the delivery of the articles to be graded to the correct one of the series of locations, which correspond to the magnitude of the forces required to produce relative motion.

4. A method of ascertaining the size and surface characteristics of resistant articles without permanent deformation thereof, consisting in forcing said articles through a gage, applying forces of changing magnitude to cause the relative movement between the gage and articles and employing the value of the force for the purpose of ascertaining said characteristics. 70

5. A method of ascertaining the size and surface characteristics of a rolling element of an anti-friction bearing without permanent deformation thereof, consisting in applying forces of changing magnitude to said element and a gauging element in contact therewith and employing the value of the force which produces the relative movement for the purpose of ascertaining said characteristics. 80

6. In apparatus for ascertaining the size and surface characteristics of resistant articles, the combination of a gage, a force transmitting means movable in a direction in which an article can enter said gage and means for ascertaining the force exerted in effecting such a relative movement between said article and gage as will cause such elastic deformation of at least one of the two to allow the article to move through the gage. 95

7. In apparatus for ascertaining the size and surface characteristics of rolling elements for anti-friction bearings, the combination of a gage means for transmitting force of changing magnitude movable in a direction in which an element can enter said gage, a series of collecting receptacles and means for automatically placing an element in a receptacle corresponding to the magnitude of the force required to pass it through a gage. 100

8. In apparatus for ascertaining the size and surface characteristics of rolling elements for anti-friction bearings, the combination of a ring gauge in which an element may be entered, a series of pressing elements each adapted to apply a force of increased magnitude in the direction of entry of said element into said gauge, separate collecting means in line and co-operating with each pressing element and means for moving said gauge to each pressing element. 105

9. In apparatus for ascertaining the size and surface characteristics of rolling elements for anti-friction bearings, the combination of a movable pressing element, a movable gauge adapted to occupy each of a series of positions in which a force of a different magnitude is exerted by a pressing element and a conduit leading to a different receptacle at each position of said series to collect the bearing elements in accordance with the pressure required to effect their passage through a gauge. 115 120

10. In apparatus for ascertaining the size 130

and surface characteristics of resistant articles, the combination of a central guide, a circular carrier adapted to reciprocate longitudinally thereon, a series of equally spaced pressing elements each adapted to exert a successively greater force movably mounted in said carrier around said guide, a conduit leading to a separate receptacle positioned below each pressing element, a table rotatable on said guide positioned between said pressing elements and conduits, a series of gauges coaxial with said pressing elements and conduits carried by said table, and means for intermittently moving 15 the table to carry each gauge successively

from one pressing element to another during successive reciprocation of the carrier.

11. In apparatus for ascertaining the size and surface characteristics of resistant articles, the combination of a gage and means for applying forces of differing magnitude in a direction adapted to press an article into said gauge and means for determining the value of the force which produced determined movement of the article in the gauge in the direction in which said force is applied.

In testimony whereof I have signed my name to this specification.

HENRY LEONARD HEATHCOTE.
